WHEELED FIGURE TOY

Charles S. Olson, Gulfport, Miss., assignor to Toy Kraft, Inc., a corporation of Ohio

Application February 1, 1945, Serial No. 575,626

3 Claims. (Cl. 46—104)

This invention relates to a wheeled figure toy and it is a particular object of the invention to provide a device of this kind which can be readily trundled by a child and which is of a character to afford amusement.

Furthermore, it is an object of the invention to provide a toy including a wheel-supported body and wherein said body is provided with a plurality of movable parts which are simultaneously operated under the action of a supporting wheel for the body.

The invention consists in the details of construction and in the combination and arrangement of the several parts of my improved wheeled figure toy whereby certain important advantages are attained, as will be hereinafter more fully set forth.

In order that my invention may be better understood, I will now proceed to describe the same with reference to the accompanying drawing, wherein:

Figure 1 is a view partly in elevation and partly in section of a wheeled figure toy constructed in accordance with an embodiment of my invention, the line of section being on the line 1—1 of Figure 2, second positions of certain of the parts being indicated by broken lines; and

Figure 2 is a view in top plan of the toy as herein comprised.

In the embodiment of the invention as illustrated in the accompanying drawing, B denotes a body including two side plates 1 substantially duplicate as to design and dimensions and each of said plates is in simulation of the body of a fowl, such as a duck, with the major portion of the upper edge a thereof straight. The forward end portion of each of the side plates 1 is provided with a relatively short upwardly directed integral lug 2 through which is directed a pivot member 3 for an elongated member 4.

The side plates 1 are spaced apart a slight distance and suitably anchored, as at 5. The upper portions of the plates 1 and interposed therebetween is a spacer block 6, the outer or top face of which is herein disclosed as substantially coplanar with the upper straight edges a of the side plates 1.

The central portion of this block 6 is provided therethrough with an inwardly inclined opening or socket 7 in which snugly fits the reduced end portion 8 of an elongated handle member 9. Extending through the block 6 and the portion 8 of the handle 9 is a holding shank 10 which, if desired, may also be directed through one of the side plates 1.

As illustrated in the accompanying drawing, the handle member 9 is straight from end to end and, when applied, extends upwardly and rearwardly from the body B when the toy is in use. The outer or free end portion of the handle member 9 has disposed therethrough a bar 11 extending desired distances beyond opposite sides of the handle member 9 to provide convenient handgrasps for the user.

The elongated member 4 is flat and in simulation of the neck and head of a fowl, such as a duck, and said member 4 is of a thickness closely approaching the space between the lugs 2 and the adjacent portions of the side plates 1 yet having free rocking movement upon the pivot member 3. The pivot member 3 is disposed through the forward marginal portion of the member 4 and said pivoted extremity of the member 4 is continued by a downwardly and inwardly directed elongated tail-piece 12 of a length to contact from above with the periphery of a supporting wheel 14 for the toy.

The wheel 14 substantially snugly extends between the lower central portions of the side plates 1 and has eccentric mounting on a supporting axle 15 around which the wheel 14 freely rotates. When the low point of the wheel 14 is uppermost, the member 4 will be at the limit of its rearward swinging movement, as illustrated by full lines 25 in Figure 1, and, of course, as the high point of the wheel 14 approaches the contact portion of the tail-piece 12, the member 4 will be swung forwardly, as indicated by broken lines in Figure 1, thus giving an animated effect to the toy when 30 in transit.

Each of the side faces of the wheel 14, which is of a disk type, has produced thereon in outline, as at 16, a number of duck legs and feet so that, as the wheel or disk 14 rotates, there will be given 35 the effect of a walking fowl.

Positioned between the upper marginal portions of the side plates 1 and of a length to extend a material distance therealong is an elongated member 17 pivotally mounted between said 40 side plates 1 by the pivot member 18. This pivot member 18 is positioned rearwardly of the longitudinal center of the member 17 and is carried by the side plates 1 of the body B.

The pivot member 18 has mounted thereon at 50 opposite sides of the member 17 the spacer washers 19 to hold the member 17 against undue movement longitudinally of the pivot member 18. The upper longitudinal edge b of the member 17 is also straight and when the forward 55 end portion of the member 17 is at the limit

of its downward swinging movement, said edge *b* is substantially coplanar with the upper or top edges *a* of the side plates 1.

The forward end portion of the member 17 is transversely enlarged to provide a depending contact member 20 which also serves to give added weight to the forward end portion of the member 17 so that said end portion will swing downwardly by gravity for constant contact by the member 20 with the upper edge of the tail-piece 12 of the member 4. The contacting edge *c* of this member 20 is rounded while the upper contacting edge *d* of the tail-piece 12 is disposed on an inbow.

The contact of the member 20 with the tail-piece 12 results in said tail-piece 12 maintaining desired contact from above with the periphery of the wheel or disk 14 and, as illustrated in Figure 1 of the drawing, the dimensions of the tail-piece 12 and of the contact member 20 are such that when the low point of the wheel or disk 14 is uppermost, the edge *d* of the member 17 will be substantially coplanar with the edges *a* of the side plates 1.

It is believed to be obvious that as the device is trundled, the resultant rotation of the wheel or disk 14, as the high point moves upwardly, will result in a forward swinging movement of the member 4 and through the action of the tail-piece 12 will be effected an upward swinging movement of the member 17 and, of course, as the high point of the wheel or disk 14 moves downwardly from uppermost position, the weight of the forward end portion of the member 17 upon the tail-piece 12 will result in the member 4 swinging rearwardly and the forward end portion of the member 17 swinging downwardly.

The member 17 at points spaced therealong is provided with the upstanding object members 21 herein disclosed as being successively of different sizes and in simulation of ducklings.

The toy in its complete assembly is one which creates the impression that a number of ducklings or other small fowl are riding on the back of a duck or other fowl, thus increasing the amusement value of the toy.

From the foregoing description it is thought to be obvious that a wheeled figure toy constructed in accordance with my invention is particularly well adapted for use by reason of the convenience and facility with which it may be assembled and operated.

I claim:

1. A device of the class described comprising

a body including two side plates, a rotatable ground-engaging member eccentrically mounted between said side plates at the lower central portion thereof, an outstanding elongated member extending and pivotally held between the forward upper portions of the side plates, a laterally directed tail-piece carried by the pivoted end portion of the elongated member and contacting the periphery of the wheel, a second elongated member disposed in a general direction lengthwise of the side plates and positioned therebetween, means for pivotally mounting said second elongated member to the side plates at a point rearwardly of the longitudinal center of said second elongated member, the forward end portion having gravity contact with the tail-piece of the first elongated member for maintaining said tail-piece in contact with the periphery of the wheel, and an outstanding object member carried by the second elongated member.

2. A device of the class described comprising a body including two side plates, a rotatable ground-engaging member eccentrically mounted between said side plates at the lower portion thereof, an outstanding elongated member extending and pivotally held between the forward upper portions of the side plates, a laterally directed tail-piece carried by the pivoted end portion of the elongated member and contacting the periphery of the wheel, a second elongated member disposed in a general direction lengthwise of the side plates and positioned therebetween, means for pivotally mounting said second elongated member to the side plates at a point rearwardly of the longitudinal center of said second elongated member, the forward end portion having gravity contact with the tail-piece of the first elongated member for maintaining said tail-piece in contact with the periphery of the wheel, an outstanding object member carried by the second elongated member, a block secured between the side plates at the upper rear portions thereof and rearwardly of the second elongated member, and an operating handle engaged with said block.

3. A device as set forth in claim 1 wherein the end portion of the second elongated member contacting with the tail-piece constitutes a member depending from the second elongated member and which also constitutes a weight to further assure the required gravitational swinging movement of the second elongated member.
